CLAIM

The ornamental design for a jewelry article including hand and cat, as shown and described.

DESCRIPTION

FIG. 1 is a front elevational view of a jewelry article including hand and cat showing the new design;

FIG. 2 is a left side elevational view thereof;

FIG. 3 is a top plan view thereof;

FIG. 4 is a right side elevational view thereof;

FIG. 5 is a bottom plan view thereof; and,

FIG. 6 is a rear elevational view thereof.

The broken lines in the figures represent portions of the jewelry article including hand and cat that form no part of the claimed design.

1 Claim, 2 Drawing Sheets
